No. 2. Ezra Ripley (a citizen of Johnson & Co., Gray, New York;
Letters Patent Design No. 132, dated 3rd July 1847.

The schedule referred to in these Letters Patent and making
part of the same:

To all to whom these presents shall come; Be it known that
I Ezra Ripley of Gray in the County of Herkimer and State

2

Des. 132

of New York have invented or produced a new design for stone plates and that the following is a full, clear and exact description of the same, reference being had to the accompanying drawings, making part of this specification, in which Fig. 1. is a view of the plate, which is of a bold configuration and is ornamented with leaves, mouldings, Diamond, and Gothic work.

On said plate is shown one half of a horizontal cylinder B which occupies nearly one third of the plate commencing about five inches from the bottom and extending upward about eighteen inches. In the centre of the plate also immediately above the cylinder is shown a Gothic niche C with diamond back ground and a fancy dome. I claim as my invention and desire to secure by letters patent the above design which is fully set forth in the drawings accompanying this description
